RADIATOR

Arthur C. Walworth, Newton, Mass.

Application July 14, 1953, Serial No. 367,785

9 Claims. (Cl. 257—262.16)

This invention relates to radiators of the fin type in which the fins can be applied to pipes already installed so as to increase the radiation without requiring removal of the piping or substitution of equipment.

In accordance with this invention the fins are secured in position by wedge keys arranged transverse to the length of the pipe as shown in the Waldron Patent No. 2,571,505, but the fins are individually applied in accordance with this invention, and the portions of the fins with which the wedges or keys engage are so designed that they may be made by a simpler and less expensive operation than in the Waldron construction.

Where space permits, also, means may be provided, in accordance with this invention, to increase the area of contact between the pipe and fin, thus to increase the efficiency of heat conduction from one to the other.

For a more complete understanding of this invention, reference may be had to the accompanying drawings in which

Figure 1 is a perspective view of a radiator fin and its attaching wedge or key.

Figure 2 is a fragmentary elevation of a pair of pipes arranged in bank and showing fins of the type shown in Figure 1 secured thereto.

Figure 3 is a detail sectional view on line 3—3 of Figure 2.

Figure 4 is an exploded perspective view showing a modification; parts being shown by dotted lines in assembled relation.

Figure 5 is a fragmentary perspective view showing a further modification.

Referring first to Figures 1, 2, and 3, the radiator fin 1, which may be stamped from sheet metal, is formed with a slot 2 extending inwardly from one face, the base of this slot being rounded at 3 so that it may engage about substantially 180° of a pipe 4 to which the fin may be secured. As is common in such fins, it may be provided with a recessed annular face portion 5 which acts to stiffen it and tends to hold it extending laterally at substantially right angles to the pipe. This fin 1 is provided with a pair of lips 6, one on each side of the notch, formed by partially cutting the material of the fin along generally parallel lines generally parallel to the sides of the slot and offsetting it laterally between its sides, spacing it away from the adjacent face of the fin by an amount sufficient to receive between them a wedge member or key 7 which is inserted between the lips 6 and the adjacent face of the fin, as shown best in Figures 2 and 3. As shown in Figure 1 the inner ends of the lips are severed from the fin so that the lips face inwardly. This wedge or key 7 may bear against the pipe 4, and hold the fin in position thereon and forced thereagainst for most effective heat conduction between them. These lips may be formed readily by a simple stamping operation and may be formed at the same time as the rib 5 and when the fin is stamped out, if desired. This provides a simple manner of forming a fin which can be attached to a pipe already in position without requiring the dismantling of the pipe and without requiring the substitution of apparatus particularly designed for radiating heat when pipes 4 such as shown in Figure 2 are already in position.

Such pipes when employed for heating are commonly arranged as shown in Figure 2, adjacent pipes being connected by a U fitting 10 into which ends of the pipes are secured. Commonly such pipes are arranged spaced

2

apart three inches on centers, which allows only a small amount of room between them, but this is sufficient for the insertion of the wedge members or keys 7 as shown in Figures 2 and 3. Of course there may be more than two pipes in one installation.

Where there is more room for the placement of the fins, a preferred construction illustrated in Figure 4 may be employed, this construction having the advantage of increased efficiency of radiation. Referring to this figure, the fin 1a is provided with the lips 6a which are spaced outwardly from the pipe over which the slotted portion 2a may be placed. A filler plate 15 shown in Figure 4 and having its side edges 16 spaced to substantially fit between the sides of the slot 2a and having an inner concaved extremity 17, is inserted within the slot. The plate member 15 may have an arcuate depression 14 therein substantially mating the corresponding depression in the adjacent face of the fin member 1a. This filler plate is provided with a lip 18 partly cut between substantially parallel side cuts and substantially parallel to the sides of the slot 2a and pressed from the material thereof, this lip being on the side of the plate 15 corresponding to the lips 6 of the fin 1a and severed at its outer end so as to face the outer edge of the plate 15 in the opposite direction to the lips 6a. This plate may be cut from the material of the fin itself. Preferably, also, the sides of the slot 2a flare slightly, so that forcing the plate portion 15 inwardly presses the sides of the plate against the sides of the slot 2a and also presses the inner concaved edge 17, as well as the base of the slot 2a, tightly against opposite sides of the pipe. The insertion of a wedge member 20 between the lips 6a and the adjacent face of the fin member 1a and between the lip 18 and the corresponding face of the plate member 15 forces the plate 15 and the fin 1a against the pipe from opposite sides. The edge 17 engages the pipe over substantially the remaining 180° of its circumference to that engaged by the base of the slot 2a. Thus the fin 1a and the plate member 15 together engage substantially about the entire circumference of the pipe. It will be noted, however, that the wedge member 20 is not in contact with the pipe as it is in the structure shown in Figures 1, 2, and 3.

Where the material of the fin or filler plate piece or both permit, a further and desirable modification shown in Figure 5 may be employed in which both ends of the lips 6b or 18b are left attached, the material of the lip or lips 6b or 18b being stretched sufficiently to be offset from the plane of the piece 1b or 15b from which it has been partly severed. In any case where the filler plate piece is employed, its lip is positioned between and generally parallel to the lips of the fin.

From the foregoing description of certain embodiments of this invention it should be clear that various changes and modifications may be made without departing from the spirit or scope of this invention.

I claim:

1. A radiator fin notched inwardly from one edge to take over and engage a pipe throughout substantially 180° of the pipe circumference, said fin having parts partly cut and bent from the general plane thereof to form a pair of lips, one on each side of said notch and generally parallel thereto in position for a key to be engaged between said lips and the adjacent face of said fin and extend across said notch and hold said fin onto a pipe extending through said notch.
2. A radiator fin notched inwardly from one edge to take over and engage a pipe throughout substantially 180° of the pipe circumference, said fin having parts partly cut and bent from the general plane thereof to form lips facing away from said notched edge in position for a key to engage back of said lips and extend across said notch and hold said fin onto a pipe extending through said notch.
3. The combination with a pipe, of a radiator fin notched inwardly from one edge, the width of said notch being substantially equal to the diameter of said pipe and having a rounded inner end to engage over said pipe throughout substantially 180° said fin having parts on opposite sides of said notch partly cut and offset from the general plane of said fin to form lips facing away from said notched edge, and a wedge engaging back of said

lips and against the adjacent face of said fin and extending across said notch in position to retain said fin assembled on said pipe.

4. A radiator fin notched inwardly from one edge to take over and engage a pipe throughout substantially 180°, a filler plate piece in said notch having a concave inner edge to engage the pipe opposite to the engagement of said fin therewith, said fin having parts partly cut and bent from the general plane thereof to form a pair of lips one on each side of said notch and generally parallel thereto, and said filler plate piece having a part partly cut therefrom and bent from the general plane thereof to form a lip generally parallel to and between said fin lips, and a wedge member extending across said fin and plate piece and between said lips and the adjacent faces of said fin and plate piece to hold said fin and plate piece assembled on the pipe.

5. A radiator fin notched inwardly from one edge to take over and engage a pipe throughout substantially 180°, a filler plate piece for said notch having a concave inner edge to engage the pipe opposite to the engagement of said fin therewith, said fin having parts partly cut from the plane thereof at each side of said notch to form lips spaced from one face of said fin and facing inwardly from said notched edge, said filler plate having a part partly cut therefrom and offset from the plane thereof to form a lip spaced from one face and facing outwardly, and a wedge member between said lips and the adjacent faces of said fin and plate holding said fin and plate assembled.

6. A radiator fin notched inwardly from one edge to take over and engage a pipe throughout substantially 180°, a filler plate piece in said notch having a concave inner edge to engage the pipe opposite to the engagement of said fin therewith, said fin having parts partly cut and bent from the general plane thereof to form a pair of lips one on each side of said notch and generally parallel thereto, and said filler plate piece having a part partly cut therefrom and bent from the general plane thereof to form a lip generally parallel to and between said fin lips, and a wedge member extending across said fin and plate piece and between said lips and the adjacent faces of said fin and plate piece to hold said fin and plate piece assembled on the pipe, the sides of said notch and filler plate piece flaring outwardly.

7. A radiator fin notched inwardly from one edge to take over and engage a pipe throughout substantially 180°, a filler plate piece for said notch having a concave inner edge to engage the pipe opposite to the engagement of said fin therewith, said fin having parts partly cut from the plane thereof at each side of said notch to form lips

spaced from one face of said fin and facing inwardly from said notched edge, said filler plate having a part partly cut therefrom and offset from the plane thereof to form a lip spaced from one face and facing outwardly, and a wedge member between said lips and the adjacent faces of said fin and plate holding said fin and plate assembled, said fin and plate having mating side edges flaring outwardly toward said notched fin edge.

8. In combination with a pipe, of a radiator fin notched inwardly from one edge, the width of said notch being substantially equal to the diameter of said pipe and the base of said notch being concaved to engage said pipe over an arc of substantially 180°, a filler plate piece for said notch having a concaved inner end engaging with said pipe for substantially the remaining 180°, said fin having parts partly cut from and offset from one face thereof on opposite sides of said notch to form tongues facing the base of said notch, and said filler plate piece having a part partly cut and offset from the corresponding face of said filler plate and forming a tongue facing oppositely to the tongues of said fin, and a wedge member engaging between said tongues and the adjacent faces of said fin and filler plate and wedging both against opposite sides of said pipe.

9. In combination with a pipe, of a radiator fin notched inwardly from one edge, the width of said notch being substantially equal to the diameter of said pipe and the base of said notch being concaved to engage said pipe over an arc of substantially 180°, a filler plate piece for said notch having a concaved inner end engaging with said pipe for substantially the remaining 180°, said fin having parts partly cut from and offset from one face thereof on opposite sides of said notch to form tongues facing the base of said notch, and said filler plate piece having a part partly cut and offset from the corresponding face of said filler plate and forming a tongue facing oppositely to the tongues of said fin, and a wedge member engaging between said tongues and the adjacent faces of said fin and filler plate and wedging both against opposite sides of said pipe, the sides of said notch and filler plate flaring toward said notched edge.
